REFRIGERATING APPARATUS

Frank Conrad, Pittsburgh, Pa., assignor to Westinghouse Electric & Manufacturing Company, East Pittsburgh, Pa., a corporation of Pennsylvania

Application January 19, 1933, Serial No. 652,535

18 Claims.

(Cl. 62—8)

My invention relates to refrigerating apparatus, and particularly to a refrigerating apparatus for air conditioning apparatus, show-case cooling, storage, cabinet cooling, et cetera, such as described in my copending application, Serial No. 653,516, filed January 25, 1933, for Air conditioning system.

My invention relates more particularly to refrigerating apparatus in which two or more evaporators are connected in parallel and are supplied with refrigerant from a common supply conduit. Heretofore, a common method of controlling the flow of refrigerant to evaporators connected in parallel has been by means of thermostatically-controlled expansion valves. These valves, however, are open to the objection that they are complicated and expensive, and require a separate connection from the refrigerant line to each evaporator.

I have found that capillary tubes are very satisfactory to distribute refrigerant to a plurality of evaporators connected in parallel, the capillary tubes also acting as fixed resistance expansion valves. Where the evaporators are not equally loaded, the capillary tubes effectively tend, as compared with conduits or other connections having only negligible resistance to flow, to prevent the least loaded evaporator from starving the others since the largest pressure difference between an inlet of the capillary tubes and the evaporators occurs at the least loaded evaporator due to the low pressure of the refrigerant therein. As the pressure difference between the ends of a tube conveying a liquid increases, the flow through the tube increases only as the square root of the increase in pressure difference, and, therefore, there is a tendency to prevent starving of the other evaporators.

A regulating valve is disposed in the supply conduit adjacent to the capillary tubes to modify the action of the capillary tubes by either manual or automatic means, thereby regulating the amount of refrigerant delivered to the cooling unit. The aforesaid automatic and manual means are also adapted to completely shut off the flow of refrigerant under certain conditions.

The capillary tubes, however, being of constant orifice, allow liquid refrigerant to be forced to the low pressure evaporators from the high-pressure condenser when the compressor stops pumping, with a resultant pressure rise in the evaporators, so that the compressor may pump liquid on starting with resultant overload thereon, which may result in breaking of the com-

pressor valves. In addition to this, if the pressure in the condenser rises unduly, more refrigerant is forced to the evaporator than the compressor can pump away with resultant overload of the compressor. To prevent overloading from these and other causes, the aforementioned regulating valve is connected in the system in such a manner that it responds to a temperature or pressure condition thereof to automatically control the flow of refrigerant to the evaporator by partially or completely stopping the flow substantially independently of the manual or automatic temperature-regulating means.

It is an object of my invention, therefore, to provide a novel control means for a plurality of evaporators connected in parallel to a common supply line.

It is another object of my invention to prevent overloading of the compressor of refrigerating apparatus.

It is a further object of my invention to provide a refrigerating system having a plurality of evaporators connected in parallel with a common supply line in which the temperatures of the evaporators are controlled without the use of complicated and expensive devices.

These and other objects are effected by my invention, as will be apparent from the following description and claims taken in accordance with the accompanying drawing, forming a part of this application, in which:

Fig. 1 is a diagrammatic view of a compression refrigerating system containing one preferred embodiment of my invention;

Fig. 2 is an enlarged diagrammatic view of the distributing and overload valve shown in Fig. 1; and,

Fig. 3 is an enlarged view of a second embodiment of the distributing and overload valve shown in Fig. 1.

Referring specifically to the drawing for a detailed description of my invention, numeral 1 designates an electric motor which drives a compressor 2 which, in turn, pumps refrigerant to a condenser 3. As refrigerant is condensed, it flows through a conduit 4 to a receiving tank 5. Refrigerant flows from the receiving tank 5 through supply conduit 6 to an expansion device generally designated at 7 and then to a cooling device 8 wherein the refrigerant absorbs heat and is drawn back to the compressor 2 through a conduit 9. A fan 11, also driven by the motor 1, forces a draft of cooling air over the compressor 2 and condenser 3. The motor is supplied with energy through conductors 10a and 10b, and a

switch 10 is provided for starting and stopping the operation of compressor 2.

The cooling device 8 is preferably of such dimensions that, as more or less refrigerant is supplied thereto, its effective cooling area is increased or decreased, and is arranged so that the full cooling area will be presented when the maximum expected load is handled by the cooling device. The cooling effect of the cooling device 8, therefore, is not dependent on the temperature thereof but is dependent on the pounds of refrigerant pumped thereto and evaporated therein per unit of time.

The cooling device 8 is comprised of a plurality of evaporators or coils 12, each having a capillary tube 13 connected to the supply conduit 6, whereby the evaporators are connected in parallel to the supply conduit. Since these tubes have constant lengths and bore diameters, the amount of refrigerant pumped to each coil 12 and, therefore, the refrigerating effect, depends on the resistance of the capillary tubes 13, and the pressure-difference between the supply line 6 and the coils 12, which pressure-difference may be varied in many ways. The capillary tubes 13 also act as expansion valves to supply low-pressure refrigerant to the cooling coils 12.

In order to modify the expansion qualities of the capillary tubes 13, a throttle valve 14 is disposed between them and the supply line. It will be noted from Fig. 2 that the inlet ends of the capillary tubes are connected to the fitting at the outlet side of the valve 14 at points which are spaced closely to each other and which are equally advanced with respect to the flow of refrigerant. It will also be noted from the drawing that the mixture of liquid and vaporous refrigerant discharged from the valve 14 is sub-divided before the liquid and vapor have appreciable opportunity for separation. This arrangement provides for uniformity of the mixture of liquid and vaporous refrigerant received by the several tubes. The valve includes an orifice 15, a seat 16 and a needle 17 which coacts with the seat 16 and opens and closes the orifice 15. The valve is normally operated by a handle 18 attached by suitable linkage 19 to the needle 17 as shown in Fig. 2. By varying the adjustment of the valve 14, the amount of refrigerant delivered to and distributed by the capillary tubes is changed, or the refrigerant is entirely cut off, and the effective area of the cooling device 8 is, therefore, also changed.

In order to operate the valve 14 automatically in response to unduly high-pressure in the cooling device 8, which may occur therein due to stopping of the compressor and other causes, and thusly prevent overloading of the compressor, a safety device including a Sylphon bellows 21 is connected by a conduit 22 to the interior of the cooling device 8. The closed end of the bellows is connected to the needle 17 so that, when the pressure in the cooling device 8 rises, the Sylphon 21 expands and forces the needle 17 into the valve orifice 15, thus closing or partly closing the valve 14 and allowing the pump 2 to lower the pressure in the coils 12. Also, when the compressor 2 stops operating, the high-pressure prevailing in the condenser 3 will force liquid refrigerant into the cooling device 8 through the unrestricted passages of the capillary tubes 13. The pressure in the cooling device 8 thereupon rises, and the valve 14 is then closed. Liquid refrigerant in the low-side of the system then vaporizes as the temperature thereof rises during the off-cycle period of the machine; the compressor, therefore, upon

starting pumps only gas and breaking of valves due to pumping liquid is prevented.

In a second embodiment of my invention, a second Sylphon bellows 23 replaces the manual adjustment 18, the remainder of the apparatus being the same. The bellows is filled with a suitable expansible liquid such as ethyl chloride and is connected by a conduit 24 to a bulb 25 which is positioned in an enclosure 26 which is to be cooled. The closed end of the bellows 23 is connected through suitable linkage 27 to the needle 17 so that, as the temperature in the enclosure 26 is lowered the bellows 23 contracts and forces the needle 17 into the orifice 15, thus closing, or partly closing, the valve 14 and thus decreasing or stopping flow of refrigerant delivered to the cooling device.

From the foregoing description, it will be apparent that I have provided a novel control means for a plurality of refrigerating evaporators which are connected in parallel to a common supply conduit, without the use of expensive and complicated devices. It is obvious that the various coils of the evaporator need not be disposed together, and that the bore and length of the capillary tube for each coil may vary so that the refrigerating effect of each coil is varied. The capillary tubes provide for distribution and expansion of the compressed refrigerant into a plurality of evaporating coils, and the valve 14 provides for modifying the expansion action of the capillary tubes, either manually or in response to the temperature of an enclosure to be cooled. The valve 14 also prevents overloading of the compressor on starting, or when running due to other causes which raise the temperature and pressure of the evaporator to a point where the compressor cannot handle the media to be exhausted therefrom without danger of breaking the compressor valves and otherwise straining the compressor.

While I have shown my invention in two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a refrigerating system, a common refrigerant supply conduit, a plurality of evaporators, and a plurality of capillary tubes connecting the evaporators in parallel to said capillary tubes for distributing and expanding refrigerant from said common supply conduit to each of said evaporators, and a valve disposed between said supply conduit and said capillary tubes, means for adjusting the valve and means independent of the adjusting means responsive to a characteristic of pressure and temperature of said system for operating the valve.

2. In a refrigerating system, a common refrigerant supply conduit, a plurality of evaporators, a plurality of capillary tubes connecting said evaporators in parallel to said capillary tubes for distributing and expanding refrigerant from said common supply conduit to each of said evaporators, and a valve disposed between said supply conduit and said capillary tubes, means for adjusting the valve and means independent of the adjusting means responsive to the pressure of said evaporator to operate the valve.

3. In a refrigerating system, a common refrigerant supply conduit, a plurality of evaporators, a plurality of capillary tubes connecting the

- evaporators in parallel to said refrigerant supply conduit for distributing and expanding refrigerant to each of said evaporators, and a manually adjustable valve disposed between said supply conduit and said tubes to modify the action of said tubes, said valve also being provided with means responsive to a characteristic of pressure and temperature of said system for operating said adjustable valve.
10. 4. In a refrigerating system in which a refrigerant is successively compressed, condensed and evaporated, an evaporator comprising a plurality of coils having separate inlets, an expansion device of constant length and orifice connected to the inlet of each evaporator coil, an adjustable valve for controlling the flow of refrigerant to said expansion devices, and means for adjusting said valve in response to the pressure of the evaporator.
15. 5. In a refrigerating system in which a refrigerant is successively compressed, condensed and evaporated, an evaporator comprising a plurality of coils having separate inlets, an expansion means of constant length and orifice connected to the inlet of each evaporator coil and an adjustable valve for controlling the flow of refrigerant to said expansion devices, said valve being adjustable both manually and in response to the pressure of the evaporator.
20. 6. In a refrigerating system in which a refrigerant is successively compressed, condensed and evaporated, an enclosure to be cooled by said system, an evaporator in heat exchange relation with said enclosure, said evaporator comprising a plurality of coils having separate inlets, an expansion means of constant length and orifice connected to the inlet of each evaporator coil, and an adjustable valve responsive to the temperature of said enclosure for controlling the flow of refrigerant to said expansion devices.
25. 7. In a refrigerating system in which a refrigerant is successively compressed, condensed and evaporated, an enclosure to be cooled by said system, an evaporator in heat exchange relation with said enclosure, said evaporator comprising a plurality of coils having separate inlets, an expansion means of constant length and orifice connected to the inlet of each evaporator coil, and an adjustable valve responsive to the temperature of said enclosure for controlling the flow of refrigerant to said expansion devices, said valve being also manually adjustable.
30. 8. In a refrigerating system in which a refrigerant is successively compressed, condensed and evaporated, an enclosure to be cooled by said system, an evaporator in heat exchange relation with said enclosure, said evaporator comprising a plurality of coils having separate inlets, an expansion means of constant length and orifice connected to the inlet of each evaporator coil, an adjustable valve responsive to the temperature of said enclosure for controlling the flow of refrigerant to said expansion devices, and means responsive to a pressure-temperature characteristic of said system for also operating said valve.
35. 9. In a refrigerating system in which a refrigerant is successively compressed, condensed and evaporated, an evaporator comprising a plurality of coils having separate refrigerant inlets, a capillary tube connected to the inlet of each evaporator coil for expanding refrigerant into the coil, a shut-off valve for stopping the flow of refrigerant through the capillary tubes to the coils, and means responsive to a pressure condi-
- tion in the coils for operating the shut-off valve.
40. 10. In a refrigerating system comprising a condenser, a liquid receiver, a plurality of evaporators of the dry type, a compressor, means for driving the compressor, and means for starting and stopping the compressor driving means; the combination of a common refrigerant supply conduit for delivering refrigerant to said evaporators from the liquid receiver, a plurality of capillary tubes connecting the evaporators in parallel to said conduit for distributing and expanding refrigerant into each evaporator, and an automatically operable valve for shutting off the flow of refrigerant from the supply conduit to the evaporators when the compressor is stopped.
45. 11. In a refrigerating system comprising a condenser, a liquid receiver, a plurality of evaporators of the dry type, a compressor, means for driving the compressor, and means for starting and stopping the compressor driving means; the combination of a common refrigerant supply conduit for delivering refrigerant to said evaporators from the liquid receiver, a plurality of capillary tubes connecting the evaporators in parallel to said conduit for distributing and expanding refrigerant into each evaporator, and a valve for shutting off the flow of refrigerant from the supply conduit to the evaporators in response to a condition resulting from stopping of the compressor.
50. 12. In refrigerating apparatus, the combination of a compressor, means for driving the compressor, means for starting and stopping the compressor and its driving means, a condenser connected to the outlet of the compressor, a liquid receiver connected to the outlet of the condenser, a plurality of evaporators of the dry type connected to the inlet of the compressor, conduit means for conveying refrigerant from the liquid receiver to the evaporators and including capillary tubes for distributing refrigerant to the evaporators, and means for shutting off flow of refrigerant through said conveying means in response to a condition in the apparatus substantially concurrent with stopping of the compressor for preventing accumulation of liquid refrigerant between the capillary tubes and the inlet of the compressor while the latter is stopped.
55. 13. Refrigerating apparatus comprising the combination of a plurality of evaporator elements of the dry type; a common liquid refrigerant supply conduit therefor; and means for expanding liquid refrigerant supplied from said conduit to said evaporator elements, for regulating said expansion and for distributing the same to the several evaporator elements comprising an expansion valve and a group of restricted flow-resistance passages, through which valve and group of passages the refrigerant flows in series and in each of which it is partially expanded, and means responsive to an operating condition of the evaporator elements for controlling said valve, whereby said valve and flow-resistance passages together effect expansion of the refrigerant, said valve regulates said expansion, and said flow-resistance passages distribute the refrigerant among the evaporator elements, said passages having their entrant ends closely spaced for proper division of refrigerant therebetween.
60. 14. Refrigerating apparatus comprising the combination of a plurality of evaporator elements arranged to effect a common cooling action, common liquid refrigerant supply means
65. 70. 75.

- therefor, and means for distributing refrigerant from said supply means to said evaporator elements and for effecting expansion and regulating the flow thereof, said last-mentioned means including a plurality of fixed restricted passages or orifices connected respectively to the inlet ends of the several evaporator elements for distributing refrigerant thereto, a valve connected between said supply means and said restricted passages or orifices for regulating the flow of the refrigerant, and means operable automatically in response to pressure of the refrigerant in said evaporator elements for regulating said valve.
15. Refrigerating apparatus comprising the combination of a plurality of evaporator elements of the dry type arranged to effect a common cooling action, common liquid refrigerant supply means therefor, and means for distributing refrigerant from said supply means to said evaporator elements and for effecting expansion and regulating the flow thereof, said last-mentioned means including a plurality of fixed elongated passages of restricted flow area connected respectively to the inlet ends of the several evaporator elements for distributing refrigerant thereto, a valve connected between said supply means and said restricted passages for regulating the flow of the refrigerant, and means operable automatically in response to an operating condition of the evaporator elements for regulating said valve, said restricted passages having their entrant ends closely spaced for proper distribution of refrigerant thereto.
35. Refrigerating apparatus comprising the combination of a plurality of evaporator elements arranged to effect a common cooling action, common liquid refrigerant supply means therefor, and means for distributing refrigerant from said supply means to said evaporator elements and for effecting expansion and regulating the flow thereof, said last-mentioned means including a plurality of tubes of restricted flow area connected respectively to the inlet ends of the several evaporator elements for distributing refrigerant thereto, a valve connected between said supply means and said restricted tubes for regulating the flow of the refrigerant, and means operable automatically in response to pressure of the refrigerant in said evaporator elements for regulating said valve.
17. In refrigerating apparatus having a plurality of evaporator elements, an expansion mechanism for said evaporator elements comprising an expansion valve, means for operating said valve in response to an operating condition of the refrigerating apparatus, a distributor fitting connected to the output side of said valve, said fitting having a plurality of orifice outlets grouped closely together and disposed at points which are equally advanced with respect to the flow of the refrigerant, said outlets communicating respectively with said evaporator elements for distributing refrigerant thereto, the expansion mechanism being constructed and arranged so that the mixture of liquid and vaporous refrigerant is subdivided by the outlets before the liquid and vapor have appreciable opportunity for separation. 5
18. In refrigerating apparatus, the combination of a plurality of evaporator elements arranged to effect a common cooling action, common liquid refrigerant supply means therefor, and means for distributing refrigerant from said supply means to said evaporator elements and for effecting expansion and regulating the flow thereof, said last-mentioned means including an expansion valve, means for operating said valve in response to an operating condition of the refrigerating apparatus, a distributor head connected to the outlet side of said valve, a plurality of tubes of restricted flow area extending from said distributor head to said evaporator elements, the inlet ends of said tubes being connected to said distributor head and arranged in a cluster and at points which are equally advanced with respect to flow of the refrigerant, the distributing and regulating means being constructed and arranged so that the mixture of liquid and vaporous refrigerant is subdivided by the tubes before the liquid and vapor have appreciable opportunity for separation. 10 15 20 25 30 35 40 45
